Inventor:

John Kirby Jr.

UNITED STATES PATENT OFFICE.

JOHN KIRBY, JR., OF DAYTON, OHIO.

HEAD-REST FOR SLEEPING-CARS.

SPECIFICATION forming part of Letters Patent No. 391,748, dated October 23, 1888.

Application filed June 21, 1888. Serial No. 277,773. (No model.)

To all whom it may concern:

Be it known that I, JOHN KIRBY, Jr., of Dayton, county of Montgomery, and State of Ohio, have invented certain new and useful Improvements in Head-Rests for Sleeping-Car Seats; and I do hereby declare that the following is a full, clear, and exact description thereof, reference being had to the accompanying drawings, which form a part of this specification.

10 My invention relates to that class of head-rests which are movable and which may be made to form wall-pockets against the partitions between the seats or berth-sections when they are made up as beds at night; and it consists in a device for attaching the head-rest to the ends of the seats in such a manner that it may be raised and sustained in an inclined position with its upholstered side out when used as a pocket, and held secure in position against 15 the partition when resting on the seat-back and in use for day travel, as more fully hereinafter described.

Figure 1 is a perspective view of a metallic plate forming one of the parts for securing the head-rest in position. Fig. 2 is a perspective view of a metallic plate forming a guide and support for the head-rest. Fig. 3 represents a portion of the head-rest with the plate shown in Fig. 1 attached. Fig. 4 is a sectional elevation showing the partition between the seats, the upper end of the seat back and end, the head-rest in position as a wall-pocket, and in dotted lines as a head-rest. Fig. 5 is a sectional elevation of the partition between the 20 seats and the upper part of a seat end, with guide and support-plate in position and the head-rest and back removed.

A represents the head-board, used to form a partition between the upper berths when they 25 are made up; B, the partition between the seat-backs, upon which the head-board is supported; C, the seat end; D, the upholstered seat-back; and E, the movable head-rest, all of which are constructed in the usual manner.

F is a metallic plate, preferably made in the 45 form shown and secured to each end of the upholstered head-rest, as more clearly shown in Fig. 3, and having a projecting wedge-shaped lug, G, which operates in slot I of a metallic guide-plate, H, one of which is secured to each 50 end of the seat.

It will be seen from the foregoing that when the head-rest is in its normal position as such, as seen by dotted lines in Fig. 4, lug G will rest and wedge itself in the pocket J, and thus 55 the head-rest is held back against the partition B.

When desired as a wall-pocket, the head-rest is raised and lug G dropped into the pocket K, as shown in Fig. 4. To replace the head-rest, it is only necessary to draw it forward and upward till lug G clears pocket K; then allow it to drop into position. By this arrangement the upholstered side of the head-rest is always exposed to the passenger. 65

I am aware that movable head-rests have been made prior to my invention, and do not, therefore, claim the same, broadly.

What I do claim is—

1. The combination, with a sleeping-car seat, 70 of a head-rest movable in guides provided with pockets to engage with lugs, whereby the head-rest may be raised and maintained in an inclined position to form a wall-pocket, substantially as shown and described.

2. A sleeping car seat whose ends extend above the seat-back, having an independent head-rest, in combination with guide-plate, as H, having slot, as I, and pocket, as K, and plate, as F, provided with lug, as G, the whole to operate substantially as shown and described. 75 80
